UNITED STATES PATENT OFFICE.

MORITZ FORST, OF NEW YORK, N. Y., ASSIGNOR OF FORTY-NINE ONE-HUNDREDTHS TO HIMSELF, SEVENTEEN ONE-HUNDREDTHS TO EMANUEL LINHARDT, SEVENTEEN ONE-HUNDREDTHS TO HARVEY N. KUTTNER, AND SEVENTEEN ONE-HUNDREDTHS TO GEORGE POHLMANN, ALL OF NEW YORK, N. Y.

NON-REFILLABLE BOTTLE.

No. 914,129.

Specification of Letters Patent.

Patented March 2, 1908.

Application filed May 18, 1906. Serial No. 433,689.

To all whom it may concern:

Be it known that I, MORITZ FORST, a citizen of the United States, and a resident of the city of New York, borough of Manhattan, in the county and State of New York, have invented a new and Improved Non-Refillable Bottle, of which the following is a full, clear, and exact description.

The object of the invention is to provide a new and improved non-refillable bottle, which is simple in construction and arranged to effectively prevent refilling of the bottle with spurious liquids by unauthorized parties, especially when the bottle is held in a horizontal position.

The invention consists of novel features and parts and combinations of the same, which will be more fully described herein-after and then pointed out in the claims.

20 A practical embodiment of the invention is represented in the accompanying drawings forming a part of this specification, in which similar characters of reference indicate corresponding parts in both views.

25 Figure 1 is a sectional side elevation of the improvement showing the bottle tilted for pouring the contents thereof; and Fig. 2 is a similar view of the same showing the bottle closed on tilting it back to a horizontal position.

The neck A of the bottle body B is provided with a contracted portion A' at the junction of the bottle neck A with the body B, and in the said contracted portion A' is secured a valve seat C, on the upper end of which is adapted to be seated a valve D made of cork or other material. The valve D is loosely mounted on a valve stem E provided with a tapering head E' extending loosely into a recess F' formed centrally on the under side of the bearing F held in the neck A directly below a cap G having an annular ring H of a compressible material, such as cork, fitting into an annular recess A' formed inside of the neck near the outer end thereof, to allow of forcing the cap G into position in the outer end of the neck A, and to prevent withdrawing of the cap G owing to the ring H fitting the annular recess A'. The bearing F is provided on its sides with lengthwise-extending grooves F² leading to radial grooves F³ formed in the outer face of the bearing F and registering at their inner

ends with a central opening G' formed in the cap G, so that when the bottle is tilted as shown in Fig. 1, then the contents of the bottle can flow through the open valve seat C and by way of the grooves F², F³ to and through the opening G' into the glass or other vessel to be filled.

The lower end of the valve stem E terminates in a cone I having flutes or grooves I' extending in the direction of the length of the cone I, and on the base of the cone is secured a weight J, preferably in the form of a ball, as indicated in the drawings. The cone I is adapted to be seated on the lower end of the valve seat C at the time the bottle is moved into a tilted position, as shown in Fig. 1, it being understood that the liquid contained in the bottle body B can flow by way of the flutes I' into and through the valve seat C and past the open valve D to the grooves F², F³, to finally pass by way of the opening G' to the glass or other receptacle to be filled. Now when the bottle is tilted back from the pouring position shown in Fig. 1 into a horizontal position, then the valve D is automatically moved to its seat immediately prior to the bottle reaching a horizontal position, it being understood that the weight J on the cone I causes the latter to slide inward on the inner end of the valve seat C, so that the head E' of the valve stem E moves the valve D into a closed position on the outer end of the valve seat C, as plainly indicated in Fig. 2. Thus the bottle before reaching a horizontal position is closed by the valve D being seated on the valve seat C, and consequently the bottle cannot be refilled with spurious liquids on holding the bottle in a horizontal position. When the bottle is in a vertical position then the valve D is firmly held to its seat by its own weight and by the combined action of the cone I and the weight J holding the head E' of the stem E down on the valve D and the latter in contact with the valve seat C.

By constructing the bearing F in the manner described, it is evident that an unauthorized person cannot pass a wire or the like into the interior of the neck A with a view to hold the valve D off its seat, as such introduced wire is not liable to pass through a pair of registering grooves F³, F² owing to the sharp angle between the said grooves.

The valve seat C is preferably provided with a lining C' of cork or other material, to properly fit the seat into the contracted portion A' of the neck A of the bottle.

5 The several parts constituting the closure for the non-refillable bottle are made of suitable material which may vary according to the liquid with which the bottle is to be filled.

Having thus described my invention, I 10 claim as new and desire to secure by Letters Patent:

1. A non-refillable bottle provided with a closure arranged in the neck of the bottle comprising a valve-seat fixed in the neck of the bottle, a valve adapted to be seated on the upper end of the said seat and having a stem projecting above and below the same, a weighted cone on the lower end of the stem of the said valve and adapted to engage the lower end of the said valve seat, a bearing held in the upper portion of the bottle neck for guiding the upper end of the valve stem, the bearing being provided with peripheral grooves and with radial grooves on the upper face thereof, the peripheral grooves leading to and communicating with the radial grooves, and an outlet cap fixed in the upper end of the bottle neck and having a central

opening in register with the inner ends of the said radial grooves.

2. A non-refillable bottle provided with a closure arranged in the neck of the bottle and comprising a valve seat fixed in the neck of the bottle, a valve adapted to be seated on the upper end of said seat, a stem having a head and on which the said valve is mounted loosely between the head and the seat, a fluted cone on the lower end of the said valve stem, a weight on the base of the cone a bearing for the head of the valve stem and held in the upper portion of the said neck, said bearing having peripheral grooves and having radial grooves on the upper face thereof, the peripheral grooves leading to the radial grooves, and an apertured cap fixed in the top of the neck and having a central aperture in register with the inner ends of the said radial grooves.

In testimony whereof I have signed my name to this specification in the presence of 50 two subscribing witnesses.

MORITZ FORST.
